PAPER RACK AND SLICER

Oswald K. Hoglund and Fred W. Herbert,
Santa Paula, Calif.

Application November 17, 1938, Serial No. 240,947

1 Claim. (Cl. 242—55.4)

(Granted under the act of March 3, 1883, as
amended April 30, 1928; 370 O. G. 757)

This application is made under the act of
March 3, 1883, as amended by the act of April
30, 1928, and the invention herein described and
claimed, if patented, may be manufactured and
used by or for the Government of the United
States of America for governmental purposes
without the payment to us of any royalty
thereon.

We hereby dedicate the invention herein de-
scribed to the free use of the people of the
United States to take effect on the granting of
a patent to us.

This invention relates to a device for cutting
rolls of paper or other similar textile materials.

One of the objects of this invention is to pro-
vide such a device which, while cutting the
paper, will automatically indicate the line along
which the next succeeding cut is to be made
where it is desired to cut the rolls of paper pro-
gressively into equal sections.

Another object of this invention is to pro-
vide a device of the type mentioned which will
hold and permit a number of rolls of paper, or
other similar material, to be simultaneously sub-
mitted to and cut by a shearing knife.

In the drawing:

Figure 1 is a plan view and Figure 2 is a front
elevational view of this invention.

Referring with more particularity to the draw-
ing in which like numerals designate like parts,
the numeral 1 denotes a base supporting two
vertical side members 2 and 3 comprising to-

gether a rack. These side members 2 and 3 each
carry slots 4 in spaced relation disposed at an
angle running downward to the front or shear-
ing end of the rack, substantially as shown.
These slots serve as bearings for the spindles 5
of the rolls of paper 6 which are mounted in
tandem in such a manner that the rolls of paper
unroll from the bottom and together are sub-
mitted to a shearing knife 7. Said shearing
knife is pivotally mounted at 8 and has a handle 10
9 for manual operation. A bar 10 is secured at
one end to said knife 7 parallel to the base of
the rack and such that a marker 11 adjustably
mounted thereon in the slot 12 will mark the top
paper when the shearing knife is brought down. 15
A guide roller 13 is provided to keep the paper
lengths together as they are submitted to the
shearing knife.

Having thus described our invention, we claim:

The combination of a paper rack and slicer 20
comprising a plurality of slotted sections in
spaced relation on vertical supports of said rack,
said slotted sections being adapted to act as
tandem bearings for spindles of rolls of paper,
a shearing mechanism horizontally disposed on 25
said rack, and adjustable means integral with
said shearing mechanism for marking a line on
the paper to indicate the next succeeding cut-
ting line.

OSWALD K. HOGLUND. 30
FRED W. HERBERT.
